(57) **CLAIM**

The ornamental design for a pixel controller, as shown and described.

DESCRIPTION

FIG. 1 is a front perspective view of a pixel controller showing my new design.

FIG. 2 is a bottom perspective view thereof.

FIG. 3 is a front elevation view thereof.

FIG. 4 is a top view thereof.

FIG. 5 is a rear elevation view thereof.

FIG. 6 is a bottom view thereof.

FIG. 7 is a left side elevation view thereof; and,

FIG. 8 is a right side elevation view thereof.
